ATTORNEY.

UNITED STATES PATENT OFFICE.

JOSEPH HARRY TYLER, OF BALTIMORE, MARYLAND.

DESIGN FOR A CAKE.

SPECIFICATION forming part of Design No. 24,787, dated October 22, 1895.

Application filed September 3, 1895. Serial No. 561,353. Term of patent 3½ years.

To all whom it may concern:

Be it known that I, JOSEPH HARRY TYLER, a citizen of the United States, residing at Baltimore, in the State of Maryland, have invented and produced a new and original Design for Cakes, of which the following is a specification.

The accompanying drawing shows a view of the obverse side and an end view of the design for cakes or crackers.

The essential features of my design consist in a flat cake having a curved bottom edge *a*, a relatively shorter curve crown or top edge *b*, and two inclined or converging side edges *c c'*, connecting said curved bottom and top edges. The greater portion of the obverse side has two sets of segment-curved cross-lines *d d'*, which extend from a curved cross-line *e* to the left and right, respectively, to the two opposite converging edges *c c'*, and give the effect or appearance of forming pits or in-

dentations *f* between the intersection of the lines. Adjacent to the curved bottom edge *a* and parallel therewith is a curved cross-line *g*. A space is left between the two curved cross-lines *e* and *g*.

The design has adjoining the lower edge two outward-bulging corners *h h'*, which produce the appearance of the receding bottom edge.

The reverse side of the cake is plain or smooth surfaced.

I claim—

The design for a cake or cracker as herein shown and described. 35

In testimony whereof I affix my signature in the presence of two witnesses.

J. HARRY TYLER.

Witnesses:

CHAS. B. MANN, Jr.,
ELMORE B. JEFFERY.
